ANIMATED ILLUMINATED SIGN

George A. Wing, Cincinnati, Ohio, assignor to
The Cincinnati Advertising Products Company,
Cincinnati, Ohio, a Corporation of Ohio

Application September 9, 1930. Serial No. 480,679

9 Claims. (Cl. 40—130)

This invention relates to an animated illuminated sign wherein is provided a translucent glass or like sign character bearing plate, a translucent edge of which plate is subjected to 5 light rays projected through a colorful translucent moving tape, or a tape otherwise treated to impart attractiveness to the character bearing plate.

An object of the invention is to provide a sign 10 of glass or the like carrying suitable indicia or characters, an edge of which sign is subjected to light rays passing through a translucent moving tape treated to change the color, or the frequency, of the light rays.

Another object is to provide a device of the 15 above type that is constructed so as to be simple, inexpensive and fool-proof, and which requires no attention or adjustment.

A further object is to provide a device of the 20 above character with means whereby the tape and light globes may readily be replaced by others to impart to the sign plate various lighting effects.

Another object is to provide a device of the 25 above character having in combination a clock, the motive power of which operates the tape moving mechanism.

These and other objects are attained by the 30 means described herein and disclosed in the accompanying drawings, in which:

Fig. 1 is a front elevational view of a sign structure of the invention, part being broken away.

Fig. 2 is a cross-sectional view taken on line 35 2—2 of Fig. 1, part being broken away.

Fig. 3 is a cross-sectional view of the device taken on line 3—3 of Fig. 1.

Fig. 4 is a wiring diagram illustrating the 40 electrical wiring arrangement of the device of the invention.

Fig. 5 is a plan view of a length of vari-colored tape employed in the device of the invention.

Fig. 6 is a front elevational view of a sign 45 structure having in combination a clock from which power is taken for moving the tape.

The device of the invention comprises a base 8 provided with feet 9 and a suitable cover 10, the 50 sides 11 of which are developed, at their upper edges, into a pair of parallel upright flanges 12 between which the translucent glass sign element or plate 13 may be disposed and secured in an upright position. Any suitable securing 55 means for the plate may be employed, for exam-

ple bolts or screws 14 passing through perforations in the flanges and the glass plate.

The sign element or plate preferably is of glass or like material, the front face 15 of which carries suitable indicia or advertising matter 16. 60 The advertising matter may be etched into the face 15, if desired.

It is to be noted that the translucent lower edge 17 of the sign plate is exposed to rays of light that may be projected upwardly by the 65 electric lamps 18 and the reflectors 19 on the base 8. The rays thus projected pass through a colored or vari-colored band of tape 20 that passes over rollers 21 at opposite ends of the base. The uppermost run 22 of the tape band 70 lies in close proximity with the edge 17 of the sign plate, and in a plane at right angles thereto. The rollers are mounted for rotation upon suitable supports 23 which are riveted, screwed or otherwise secured to the base. The supports 75 also may provide a mounting for the lamp sockets 24 in which the electric lamps 18 are mounted. At 25 are indicated clamps for mounting the lamp sockets.

Means are provided for continuously moving 80 the vari-colored band of type 20, which may be formed of celluloid or similar transparent film material. Said means comprises a constant speed electrical motor 26, the shaft of which is geared to a counter shaft 27 carrying at one 85 end thereof a sprocket-like member 28 provided with teeth 29 adapted to engage in the rows of spaced parallel openings 30 formed in the continuous band 20. As indicated in Fig. 1, the sprocket member 28 is disposed between a pair 90 of the rollers 21, and is so located with respect to a line passing through the axes of the roller 21, as to provide for considerable contact with the band 20. This relationship is effected by 95 disposing the periphery of the sprocket member in substantially a line with the plane passing through the axes of the pair of rollers 21. As indicated in the wiring diagram of Fig. 4, the lamps and motor 26 are electrically connected, 100 in parallel relationship. The cover 10 of the device may be provided with suitable ventilating openings 32 located to preclude emission of light rays from the interior of the device, and the ends of the device are closed by end plates 33. 105

As indicated in Fig. 5, the band of tape 20 may be streaked with various colors, the streaked and colored areas being represented by the character 34. The streaked areas preferably are translucent, but it is to be understood 110

that one or more of them may be opaque or of clear transparency, depending upon the lighting effect desired. From the foregoing it should be apparent that electrical energization of the lamps and motor will cause the lamps to project their rays through the vari-colored band 20 and onto the lower edge 17 of the sign plate, as the band is moved by reason of operation of the motor. An effective, animated and illuminated sign thereby is produced, which presents a very attractive appearance. The sign plate may have a transparent or opaque back, depending upon the effect to be produced, and the band 20 may be so treated as to project light rays corresponding to trade-mark colors or the like. A flickering type of sign may be produced by coating the band at intervals with material or paint that is opaque.

In Fig. 6 is illustrated a sign plate 35, similar to 15 and mounted in the same manner upon a base or support 36 having disposed at the front thereof a time keeping device 37, the motor 38 of which drives a sprocket 39 over which the tape may pass. In this embodiment, the band 25 40 passes over the sprocket 39 and a pair of rollers 41 at opposite ends of the device, the sprocket and rollers being disposed in triangular relationship. As in the first form of the device the uppermost run 42 of the tape is located adjacent to and in parallelism with the lower edge 30 of the sign plate. Lamps similar to those shown in Fig. 2, are indicated by 43. The band of tape 40 may be identical with the band 20 of Fig. 5, and may be readily replaced by bands decorated 35 in any suitable manner.

From the foregoing it should be apparent that a device constructed in accordance with the invention will provide a very effective and attractive sign, the mechanism of which is constant of operation, and which requires no adjusting or other attention. Furthermore, the devices are inexpensive of manufacture. It is to be understood that various modifications and changes in structural details of the device may 45 be made within the scope of the claims without departing from the spirit of the invention.

What is claimed is:

1. In an animated illuminated sign, the combination with a sign plate of translucent material bearing a display matter, and a supporting means therefor, of a source of light arranged to project rays only upon one edge of the sign plate, a transparent tape arranged to move intermediate the sign plate and the source of light, said tape being vari-colored to change the character of the light rays, and means for transmitting motion to the tape.
2. In an animated illuminated sign, the combination with a sign plate of translucent material bearing display matter, and a supporting means therefor, of a source of light arranged to project rays only upon one edge of the sign plate, a transparent tape arranged to move intermediate the sign plate and the source of light, said tape being vari-colored to change the character of the light rays, an electric motor driven means, and means for transmitting motion of the motor driven means to the tape for effecting continuous longitudinal movement thereof.
3. In a device of the class described the combination of a support and a cover therefor, a sign plate of translucent material, means on the cover for mounting the plate with an edge

thereof exposed to the interior of the cover, a source of light within the cover and arranged to project light rays toward the said edge of the sign plate, a constant speed electric motor, a continuous perforate band of vari-colored tape disposed within the cover, means for supporting the tape for movement adjacent the translucent edge of the sign plate, and power transmitting means comprising a sprocket driven by the motor and having teeth engaging the perforations of the band.

4. In an animated illuminated sign, the combination with a sign plate of translucent material bearing display matter, and a supporting means therefor, of a source of light arranged to project rays only upon one edge of the sign plate, a transparent tape arranged to move intermediate the sign plate and the source of light, said tape having alternate opaque and translucent sections, and an electric motor driven means for transmitting motion to the tape.

5. In an animated illuminated sign, the combination with a sign plate of translucent material bearing display matter, and a supporting means therefor, of a source of light, arranged to project rays only upon one edge of the sign plate, a transparent tape arranged to move intermediate the sign plate and the source of light, said tape having alternate opaque and translucent sections, an electric motor driven means associated with the tape for effecting continuous longitudinal movement thereof.

6. In a device of the class described the combination of a support and a cover therefor, a sign plate of translucent material bearing display matter, means on the cover for mounting the plate with an edge exposed to the interior of the cover, a source of light within the cover and arranged to project light rays toward the said edge of the sign plate, a motor, a continuous band of tape having alternate opaque and translucent sections and disposed within the cover, means for supporting the tape intermediate the source of light and the edge of the sign plate for movement adjacent to and in the direction of extension of the aforesaid edge of the sign plate, and power transmitting means between the band and the motor.

7. In a device of the class described the combination of a support and a cover therefor, a sign plate of translucent material bearing display matter, means on the cover for mounting the plate with an edge exposed to the interior of the cover, a source of light within the cover and arranged to project light rays toward the said edge of the sign plate, a constant speed electric motor, a continuous perforate band of tape having alternate opaque and translucent sections, and disposed within the cover, means for supporting the tape for movement adjacent the translucent edge of the sign plate, and power transmitting means comprising a sprocket driven by the motor and having teeth engaging the perforations of the band.

8. In a device of the class described the combination of a support and a cover therefor, a sign plate of translucent material bearing display matter, means on the cover for mounting the plate with an edge exposed to the interior of the cover, a source of light within the cover and arranged to project light rays toward the said edge of the sign plate, a motor, a continuous band of vari-colored tape disposed within the cover, means for supporting the tape inter-

mediate the source of light and the edge of the sign plate for movement adjacent to and in the direction of extension of the aforesaid edge of the sign plate, and power transmitting means 5 between the band and the motor.

9. In an animated illuminated sign, the combination with a sign plate of light pervious material bearing display matter, and a supporting

means therefor, of a source of light arranged to project rays only upon one edge of the sign plate, a transparent tape arranged to move intermediate the sign plate and the source of light, said tape being vari-colored to change the 80 character of the light rays, and means for transmitting motion to the tape.
